[57] CLAIM

The ornamental design for a plastic container for liquids, as shown and described.

DESCRIPTION

FIG. 1 is a side elevational view of a plastic container for liquids embodying my new design;

FIG. 2 is an elevational view looking from the left of FIG. 1, the opposite side being a mirror image thereof;

FIG. 3 is a side elevational view of a second embodiment of my new design which is identical to FIG. 1 except for the neck of the container;

FIG. 4 is a plan view of the embodiment shown in FIG. 1.

FIG. 1

FIG. 2

FIG. 3

FIG. 4
